UNITED STATES PATENT OFFICE.

FRANK J. PRASIL AND JAMES G. BETAR, OF CHICAGO, ILLINOIS.

FABRIC-RENOVATING BRUSH.

1,208,001.

Specification of Letters Patent. Patented Dec. 12, 1916.

Application filed February 25, 1916. Serial No. 80,478.

To all whom it may concern:

Be it known that we, FRANK J. PRASIL and JAMES G. BETAR, citizens of the United States, residing at Chicago, in the county of Cook and State of Illinois, have invented a new and useful Improvement in Fabric-Renovating Brushes, of which the following is a specification.

This invention relates to devices for renovating fabrics having a nap or piled-surface including such as velvet or plush.

An object of this invention resides in the production of a simple and efficient device for renovating, renewing, or restoring fabrics by raising the projecting surface-fibers of the nap thereof, to their natural or original position to present a restored, live, or smooth surface.

Another object of this invention is the provision of a device for treating fabrics with alternate steam and dry brushing.

It is also an object to provide a device of this character which shall be inexpensive to manufacture, simple in construction and therefore easily maintained.

With these and other objects in view our invention consists in the novel construction, combination, association, and relative position of the parts and members shown in the accompanying drawings, hereinafter described, and particularly pointed out in the appended claims.

Referring to the drawing in which like reference characters indicate like or corresponding parts: Figure 1 is a side elevation showing our invention and Fig. 2 is a longitudinal cross section thereof. Fig. 3 is a cross section taken on line 3-3 of Fig. 2, showing the brush and chambers. Fig. 4, a plan view of the brush-back showing the steam discharge openings.

In the preferred construction herein illustrated our invention is embodied in a body 5 having an interior horizontal partition 6 which divides the interior thereof into an upper steam chamber 7 and a lower steam chamber 8. An arched ceiling 7^A may be provided for the upper chamber 7, and a horizontal perforated floor 8^A for the lower chamber 8, although this floor could be entirely omitted by simply providing a pair of cast lugs (not shown) to the front and rear walls, marked respectively 5^A and 5^B of the body 5, which lugs would retain thereto, the brush back 9, by means of screws 9^B passing through the openings 9^A. The floor 8^A

is provided with a plurality of perforations 8^B which register with the perforations 9^C arranged between the bristles 9^D in the brush-back 9. A main steam pipe 10 constantly conveys steam into the hot or upper, steam chamber 7, a drain cock 11 is provided for the purpose of draining the chamber 7 of any condensed steam. The lower, or brush chamber 8, is supplied at intervals and as desired, 60 with steam through an adjacent pipe 12 having a connection at 12^A with the main pipe 10. A valve 13 controls the steam supply to said brush chamber 8. The ends of the two steam supplying pipes pass through and are entirely enveloped by the operating handle 14; and the end of the main supply pipe 10 is connected with a flexible steam hose 15 which permits the movement of the entire device. 75

In the process of renovation the fabric may first be given a steam brushing involving the application of steam which passes from the lower chamber 8 through the brush-back 9 and between the bristles 9^D and immediately following this, the fabric is treated with a dry brushing utilizing the heat from the upper or hot chamber 7, thereby drying the fabric and removing any particles of condensed steam. 80

From the above description and attached illustrations it is obvious that a simple and novel device is provided which affords the application of alternate steam and hot brushing for renovating fabrics by thoroughly and effectively acting upon the fibers of the nap. 85

It is also clear that the body of fabrics treated with this device is not subject to shrinkage for the reason that hairs or fibers of such fabrics are treated directly from above and not from the bottom through the body. 90

It is thought that the foregoing description and illustrations clearly disclose the invention, hence a more extended explanation is omitted. 100

We claim:

1. In a device of the character described, the combination of a body having a pair of independent steam chambers, separate means for conveying steam to said chambers and a brush communicating with one of said chambers and adapted for receiving steam therefrom. 105

2. In a device of the character described, the combination of a body having a pair 110

of independent steam chambers, means for constantly maintaining steam in one of said chambers, a brush having a perforated back communicating with the other of said chambers, and means for controlling the passage of steam to said brush.

- 5 3. In a device of the character described, the combination of a body having upper and lower independent chambers, means for 10 constantly maintaining steam in said upper chamber, a brush having a perforated back, said brush being attached to said lower chamber and communicating with same, means for discharging steam through said 15 lower chamber and said brush at desired intervals of time.

4. In a device of the character described, the combination of a hollow body having a horizontal partition therein dividing the 20 interior thereof into an upper chamber and a lower chamber, a main pipe adapted for constantly conveying steam to said upper chamber, an associate pipe communicating with said main pipe for conveying steam to said lower chamber, a brush attached to said lower chamber and a valve for controlling the passage of steam through said 25 lower chamber and brush.

5. In a device of the character described, 30 the combination of a body having an imperforate partition dividing the interior

thereof into an upper chamber and a lower chamber, a main pipe adapted for constantly maintaining steam in said upper chamber, means for draining said upper 35 chamber, a pipe communicating with said main pipe and said lower chamber, a valve for said pipe communicating with said lower chamber for controlling the passage of steam thereto, a handle adjacent said 40 body enveloping both of said pipes, and a brush having a perforated back, said perforations arranged between the bristles and communicating with said lower chamber.

6. In a device of the character described, 45 the combination of a body having an imperforate partition dividing the interior of same into independent upper and lower chambers, a main pipe adapted for constantly maintaining steam in said upper 50 chamber, a pipe controlled by a valve for discharging steam into said lower chamber, a handle adjacent said body enveloping the ends of said pipes leading to said chambers, a fixed perforated floor for said 55 lower chamber, and a removable brush having a perforated back.

In witness whereof, we have hereunto subscribed our names this 10th day of February, 1916.

FRANK J. PRASIL.
JAMES G. BETAR.
